UNITED STATES PATENT OFFICE

CHARLES D. YOUNG, OF HAVERFORD, PENNSYLVANIA

SUPPORTING AND RETAINING MEANS FOR RAILS

Application filed December 24, 1931. Serial No. 583,015.

This invention relates to supporting and retaining means for rails, and more particularly to spring fasteners or keys for retaining rails upon underlying tie plates, though 5 in using the term "tie plate" herein, I mean to include any form of plate, tie or foundation, upon which the base of a rail is adapted to be supported.

In my pending application for U. S. Letters Patent, Serial No. 569,357, filed October 17, 1931, I have referred to the advantages of the use of rail retaining means which are positioned at a predetermined clearance above the top surface of a rail flange to permit the rail to move with relation to the tie plate within certain desired limits, while preventing excessive movement in such direction.

The principal object of the present invention is to provide in combination with a tie plate and rail retaining means of this character, wherein the rail is free to move with relation to the tie plate within certain limits and without causing the ties to be loosened 20 from the underlying ballast, additional means, preferably in the form of a relatively weak spring key, for engaging the top surface of the rail with sufficient pressure to prevent objectionable noise or chatter incident to the passage of heavy loads, and also to serve as an anti-creeper by opposing movement of the rails in the direction of their length.

Other objects and advantages characterizing my present invention will become more 35 fully apparent from the description herein-after of one example or form which the invention may take, having reference to the accompanying drawing, whereof:

Fig. I represents a plan view, with the rail shown in section, of a rail, tie plate and rail retaining device assembled according to the practice of my invention; and,

Fig. II represents a cross-section of the same, taken as indicated by the lines II-II of Fig. I.

In the drawing a rail of standard form is designated at 1, and its base is designated at 2. The rail base is seated between upstanding longitudinal ribs 3 on an underlying tie plate 4. The tie plate 4 is in turn supported upon

a tie 5 to which it is secured by means of screw spikes 6, though other means may obviously be employed for affixing the tie plate to the tie. As shown at the left hand side of the figures of the drawing, the tie plate 4 is formed with an integral projection 7 which in its preferred form is in the shape of a hook and which projects above the rail base 2 clear of its top surface, the clearance being such as to permit limited vertical movement 55 of the rail base with respect to the tie plate 4. As shown in Fig. I, the hook shaped projection 7 merges with the longitudinal rib 3 at that side of the tie plate to afford a seating abutment for the corresponding edge of 60 the rail base.

At the other side of the tie plate there is shown a fulcrum member 8, which in the instant example constitutes a separate attachment rather than an integral part of the tie 70 plate, the fulcrum member being in the form of a stirrup. The downturned ends 9 of the stirrup 8 are passed through vertical slots 10 in the tie plate and bent over to lie in a horizontal plane, being accommodated within a 75 recess 11 of corresponding size at the bottom of the tie plate. At the underside of the central portion of the fulcrum member 8, a smoothly curved bearing surface 12 is provided for engagement with a spring key 80 which is comprehensively designated at 13. Near the vertical slots 10 the tie plate is formed with a boss 14 having a comparatively sharp edge 15.

The spring key 13 in the present example 85 is made from flat stock and bent to form a spring loop 16. One end 17 of the spring key 13 is sharply bent downward and adapted for engagement with the inner edge 15 of the tie plate boss 14. The other end 18 of the 90 spring key 13 projects laterally above the rail base 2 at a distance therefrom substantially corresponding to the clearance between the hook-shaped projection 7 and the rail base at the other side of the rail. Intermediate the 95 ends 17 and 18 of the spring key there is a smoothly curved portion 19 which is adapted to engage beneath the curved surfaces 12 at the underside of the stirrup 8. Welded to the spring key 13 near its inner end there is 100

an additional spring key 20 which is curved and when the key is in its normal position is so disposed as to bear upon the top surfaces of the rail base with pressure engagement. Whereas the spring key 13 is relatively thick and strong, the spring key 20 is relatively thin and weak.

The manner of assembling the spring key 13 and the relatively weak spring key 20 associated therewith is as follows. The ends 17 and 18 of the spring key 13 are inserted between the stirrup 8 and the boss 14 of the tie plate 4 by pinching the ends together, and the key is thereafter driven by delivering a blow upon the back of the spring loop 16 to cause the key to move inward to the point where its end 17 catches over the edge 15 of the tie plate boss 14. When so driven, the spring loop 16 will expand to cause the key to be seated in its predetermined proper position, and the flat end 18 will project over the rail base 2. To disengage the key 13 from the tie plate 4, it is merely necessary to compress the spring loop 16, as by a wedge applied beneath the loop, and then to apply a force in a direction transverse to the rail to cause the key to move outward.

When the parts are assembled, as shown in the drawing, the pressure exerted by the relatively weak spring key 20 is such as to offer considerable resistance against creeping or movement of the rail in the direction of its length. Moreover, the spring key 20 by offering resistance to vertical movement of the rail material reduces the chatter or noise which is characteristic of rails which are free to move up and down on their tie plates. Though exerting sufficient pressure to accomplish the above described functions, the spring key 20 is nevertheless sufficiently resilient to permit vertical movement of the rail with relation to the tie plate where the forces acting upon the rail might otherwise cause the ties to be loosened from the underlying ballast. It is to be understood, of course, that along the length of one rail a large number of spring keys are utilized, and though reference is made herein solely to the action which takes place at one tie plate, the number of spring keys associated with one rail is such that their cumulative effect produces the desired pressure upon that rail.

While I have described a particular type of tie plate and particular types of retaining members associated therewith, it will be apparent that various changes may be made in the form of these elements without departing from the spirit of my invention as defined in the annexed claims.

Having thus described my invention, I claim:

1. In combination, a rail, a tie plate having a projection at one side of the rail extending over the rail base to limit its vertical movement with respect to the tie plate, and retain-

ing means on the tie plate at the other side of the rail comprising a relatively strong spring key projecting above the rail base clear of its top surface, and a relatively weak spring key engaging the top surface of the rail base.

2. In combination, a rail, a tie plate having a seat portion for the base of the rail and a projection at one side of the rail extending over the rail base to limit its vertical movement with respect to the tie plate, and retaining means caught on said tie plate at the other side of the rail comprising a relatively strong spring key projecting above the rail base with clearance from its top surface, and a relatively weak spring key engaging the top surface of the rail base.

3. In combination, a rail, a tie plate having a hook-shaped projection at one side of the rail extending over the rail base to limit its vertical movement with respect to the tie plate, and retaining means caught on said tie plate at the other side of the rail comprising a relatively strong spring key having the end thereof projecting above the rail base with predetermined clearance from its top surface, and a relatively weak spring key engaging the top surface of the rail base.

In testimony whereof, I have hereunto signed my name at Philadelphia, Pennsylvania, this 18th day of December, 1931.

CHARLES D. YOUNG.
